Attorney.

UNITED STATES PATENT OFFICE.

A. GUSTAF SAHLQVIST, OF BROOKLYN, NEW YORK.

AWNING.

SPECIFICATION forming part of Letters Patent No. 258,319, dated May 23, 1882.

Application filed February 20, 1882. (No model.)

To all whom it may concern:

Be it known that I, A. GUSTAF SAHLQVIST, a citizen of Sweden, and a resident of Brooklyn, in the county of Kings and State of New York, have invented certain new and useful Improvements in Awnings, of which the following is a specification.

The object of my invention is to provide cheap and convenient improved means for raising and lowering awnings—such as are used for shading windows and stores—and uniformly folding and unfolding the awning-canvas automatically by such raising and lowering, respectively.

15 The invention consists in the combination of parts constructed as hereinafter described and claimed, with reference to the accompanying drawings, in which—

20 Figure 1 represents a perspective view of a partly-opened awning constructed according to my invention, the canvas being removed. Fig. 2 is a vertical section of the same with the canvas partly folded.

Similar letters of reference indicate like 25 parts.

A is the window-frame, the sashes of which are not shown.

20 B B' is the ordinary U-shaped iron frame, to which the canvas is fastened, and the lower ends of which are hinged or pivoted to lugs a, secured to the frame A. From the horizontal bar B' of the frame B B' the ordinary canvas-supporting cords, b, run over a roller, C, to which their inner ends are attached. The roller C is 35 mounted in lugs or bearings D, attached to or at about the upper end of the frame A, and to which said roller C is attached one end of the operating-cord c, which thence runs down and underneath a pulley, E, bracketed to or at the 40 lower end of the frame A. The cords b and the cord c are wound upon the roller C in opposite directions, as shown in the drawings, so that the pulling of the cord c in the direction of the arrows I will unwind the said cord from the 45 roller C, while at the same time the cords b will wind upon the roller C in direction of arrow 2, thereby shortening the distance between the roller C and horizontal bar B' of the awning-frame until the said bar is brought up close 50 to the said roller. When so folded the frame B

B' is still projected a little forward of the vertical position, sufficiently to allow the awning to drop or be lowered by allowing the operating-cord c to again wind upon the roller C.

For very large awnings, instead of the cord 55 c, the following mechanism, to which, however, I lay no claim, might be substituted:

Upon one end of the roller C is attached a conical wheel, d, gearing into a similar wheel, e, on the upper end of a vertical rod, F, mounted 60 in bearings f upon the frame A, and upon the lower end of the said shaft F is another conical wheel, f', gearing with a similar wheel, g, which is mounted upon a crank-shaft, G, which latter may be arranged to operate either from inside or outside of the window. 65

In an awning intended to shade the sidewalk the vertical bars B of the frame B B' should be omitted, and the horizontal bar B' should be provided with end rollers arranged to run 70 upon the ordinary inclined frame-work on which such awnings are supported.

H is the awning-canvas, attached with its forward edge at m to the horizontal bar B', and with its rear or inner edge at n to the upper 75 edge of the frame A above the roller C. In order to fold the canvas H uniformly and keep it from being entangled or extended to bag out in the wind, the said canvas is provided at suitable and preferably equal intervals with rings 80 h, which are sewed to the canvas and threaded on the cords b, so that, when the cords b b are wound upon the roller C, by the pulling of the cord c the rings h will slide together upon the cords b, between the roller C and the bar B', 85 and consequently the portions of the canvas intervening between the said rings h will thus be tucked in equal folds side by side and held together between the said roller and bar.

It is evident that in lowering the frame B B' 90 the canvas H will be stretched out evenly upon the supporting-cords b b.

Having thus described my invention, I claim as new and desire to secure by Letters Patent—

1. The combination of the canvas H and a 95 stiffening-bar, B', attached to said canvas, with the supporting-cords b, operating-cords c, and roller C, said cords being secured by their ends to wind in opposite directions upon the roller C, so that the unwinding of the cord c will wind 100

the cords *b*, and vice versa, substantially as set forth.

2. In an awning, the combination of the hinge-frame *B* *B'*, the roller *C*, the canvas-supporting cords *b*, attached with their ends to the frame *B*, and roller *C*, and the operating-cord *c*, wound upon the roller *C* in opposite direction to that of the cords *b*, substantially as set forth.
- 10 3. In an awning, the combination, with the bar *B'*, connecting the front ends of the canvas-supporting cords *b*, and with the roller *C*, and operating-cord *c*, the said cords *b* and *c* being wound on the roller in opposite directions,

as described, of a canvas, *H*, having rings *h*, 15 attached at intervals to slide on the cords *b*, for folding and unfolding the canvas by the winding and unwinding, respectively, of the cords *b*, substantially as specified.

In testimony that I claim the foregoing as 20 my invention I have signed my name, in presence of two witnesses, this 17th day of February, 1882.

A. GUSTAF SAHLQVIST.
